UNITED STATES PATENT OFFICE.

ALBAN H. REID, OF PHILADELPHIA, PENNSYLVANIA.

PASTEURIZED-LIQUID-HOLDING APPARATUS.

1,052,963.

Specification of Letters Patent. Patented Feb. 11, 1913.

Application filed November 12, 1910. Serial No. 591,975.

To all whom it may concern:

Be it known that I, ALBAN H. REID, a citizen of the United States, residing at Philadelphia, in the county of Philadelphia and State of Pennsylvania, have invented 5 certain new and useful Improvements in Pasteurized-Liquid-Holding Apparatus, of which the following is a specification, reference being had therein to the accompanying 10 drawing.

This invention relates to pasteurizing apparatus and more particularly to a pasteurized-liquid holding device for holding heated or pasteurized milk for a predetermined 15 time to effect thorough and complete destruction of bacteria.

The invention comprises, generally, a suitable receptacle or housing divided into a series of compartments formed by spaced 20 partitions each partition being provided with a liquid-receiving holder or trough, from the base of which extends a pipe or tube the receptacle being further provided with means for circulating the liquid through 25 and discharging the same from the receptacle, and with means for successively emptying the respective compartments.

The invention comprises, more specifically, a suitable housing or receptacle, preferably 30 to form a cylindrical chamber in which are arranged at intervals suitable partitions dividing the chamber into a number of compartments each partition having disposed at one side, and preferably at its upper end, a 35 trough or the like, from the base of which a pipe or tube extends downwardly and alongside the partition, discharging at the bottom of the chamber into the compartment in which the pipe is located the receptacle being also provided with suitable feed and 40 discharge pipes which lead into and out of the chamber, and with means for emptying each compartment.

The invention consists, also, in the novel 45 construction and arrangement of parts, as hereinafter fully described and claimed.

In the accompanying drawings, Figure 1 is a view in perspective of the holding device, with a portion of the front wall thereof 50 of broken away; Fig. 2 is a vertical longitudinal section of the same taken on the line *a—a* of Fig. 3; Fig. 3 is a vertical transverse section taken on the line *b—b* of Fig. 55 2; and Fig. 4 is a perspective view of one of the partition-members detached.

In these drawings, 1 designates a receptacle or housing mounted upon supporting

feet or standards 2. As a matter of convenient and effective arrangement, the receptacle 1 is approximately cylindrical in 60 form, and is provided at its upper portion with a hinged closure 3 of appropriate construction and arrangement to provide for absolutely air-tight closing of the housing and the retention of the heat of the treated 65 liquid. Leading into the receptacle at one end is a feed-pipe 4 for introducing the pasteurized milk therein, the portion 4^a within the receptacle extending downwardly to near the bottom of the same, as shown. 70 At the opposite end of the receptacle is a stand-pipe 5 provided at its upper end with a funnel 5^a, or the like. The stand-pipe constitutes a means of discharge from the receptacle, and is removably mounted in a 75 liquid-tight coupling member 5^b, from which extends a discharge pipe or nozzle 5^c.

Within the receptacle are disposed, at intervals, partitions or plates 6, equidistantly arranged to divide the chamber into a series 80 of compartments 7, the edges of the plates being connected liquid-tight to the walls of the chamber. Each partition has, at its upper end, a holder or trough 8, from the base of which extends downwardly a semi-circular pipe or tube 9 alongside its respective partition and discharges at its lower end into the base of the compartment in which it is located, as shown. The front wall 8^a of the holder or trough is relatively lower 90 than the opposite wall 8^b of said trough. Each partition, at its lower end, is provided with an opening therethrough closed by a valve or other controlling device which may, 95 as shown, be in the form of a plug or valve, 8^c, adapted to be removed from the opening by hand or otherwise.

Assuming that the valves 8^c in the several partitions are closed and that the closure 3 is in closed position, the heated milk or 100 other liquid, fed in through the feed-pipe 4, enters the first compartment and fills it. Eventually, the milk will overflow the low wall 8^a and pass into the trough, and then 105 downwardly through the half-round pipe 9 and escape therefrom, at the bottom, into the next compartment. Thereupon, the milk will rise in this second compartment and pass over the low wall of the next trough, and then into the next compartment; and so on throughout the series. 110 When all of the compartments become filled and the milk rises in the last one, it finds its discharge through the upper end of the

stand-pipe 5, through which it flows downwardly and escapes through the discharge pipe or nozzle 5^c into a cooler or receptacle.

In the operation of the apparatus, the 5 milk from the pasteurizer at the usual temperature of from 140° to 145° F. is fed continuously into the receiving end of the receptacle and filling the several compartments in succession in the manner described, 10 it is finally discharged through pipe 5^c, it requiring about thirty minutes in an apparatus of the form and size herein shown for the last compartment to become filled. All 15 the milk passing through the apparatus is therefore subjected for a period of thirty minutes to the temperature at which it entered, which action is sufficient to destroy all the pathogenic organisms therein.

After the supply of milk to the receptacle 20 has been cut off and, when the level of the milk, in the last compartment, falls below the discharge stand-pipe, the compartments will be left filled. Some means must be provided therefore for emptying the apparatus. This is effected by removing said 25 stand-pipe from the coupling-member 5^b and successively opening the valved orifices in the lower portion of the several partitions, beginning with that nearest the stand-pipe. The milk or other liquid will, then, 30 flow directly through the valved openings and out through the discharge nozzle or pipe 5^c.

It will be understood that while my invention is utilized particularly for milk, it is also capable of use in connection with other pasteurized liquids.

An important feature of this improved holding device is that the milk does not require to be heated in the pasteurizer to a 40 higher temperature than from 140 to 145° and, by being held approximately thirty minutes at this temperature, more valuable results are accomplished than by heating the 45 milk to a temperature of from 160 to 165°. Moreover, the device provides for a thorough circulation of the milk, and by maintaining it at the specified temperature, for approximately thirty minutes, only an al- 50 most inappreciable decrease in temperature results, from the time the milk enters the holder until it is discharged.

It is known that, if milk is permitted to 55 set for any time, the cream thereof is liable to rise to the surface. The provision, therefore, of the trough at the upper end of each partition is that they may perform an important function: As already described, the milk rises in the respective compartment 60 and overflows into the trough and, thence, through the pipe or tube 9 into the next-succeeding compartment. In this form of overflow-trough, the cream flows from the

surface of the milk into the trough and is carried down to the bottom of the next compartment, the milk following the cream in its downward flow, whereby the cream is kept constantly mixed with the milk, in each compartment and thereby avoiding all necessity of stirring, as usual, and which would, 70 of course, disturb the general and uniform flow of the milk through the holding device.

While I have herein described my invention in detail, it is to be understood that I do not limit myself to such details except in 75 so far as they may be specified in the claims.

Having thus fully described my invention, what I desire to secure by Letters-Patent is:

1. In a pasteurized-liquid holding apparatus, the combination of a receptacle provided with inlet and outlet openings, a plurality of partitions dividing the receptacle into a series of compartments, lateral elongated collecting troughs on the partitions 85 communicating with the upper portion of one compartment, each of said troughs having a contracted channel leading downwardly therefrom and communicating at its lower end at or near the base of the next 90 compartment, and means for circulating the pasteurized-liquid through said compartments.

2. In a pasteurized-liquid holding apparatus, the combination of a receptacle provided with inlet and outlet openings, a plurality of partitions therein dividing the receptacle into a number of compartments, lateral elongated shallow collecting troughs at the upper end of the compartments each 100 communicating with the upper portion of one compartment, and a pipe leading downwardly from each of the troughs and communicating at its lower end with the base of the next compartment.

3. In a pasteurized-liquid holding apparatus, the combination of a receptacle provided with inlet and outlet openings, and with a series of normally communicating compartments, a removable stand-pipe applied to the outlet opening in the rear compartment, said compartments being provided near their bases with normally closed valved openings affording when said valves are opened, a direct communication from 110 one compartment to the next, whereby by the removal of the stand-pipe and the opening of the valves, the contents of the receptacle will flow outwardly through the outlet opening.

In testimony whereof I affix my signature in presence of two witnesses.

ALBAN H. REID.
